UNITED STATES PATENT OFFICE.

WILLIAM A. KELSO, OF PHILIPSBURG, NEW JERSEY, ASSIGNOR OF ONE-HALF TO FRANK A. HILBURN AND ONE-SIXTH TO ARTHUR RICHARDS, OF EASTON, PENNSYLVANIA.

ROTARY ENGINE.

No. 838,029.

Specification of Letters Patent.

Patented Dec. 11, 1906.

Application filed February 12, 1906. Serial No. 300,766.

To all whom it may concern:

Be it known that I, WILLIAM A. KELSO, a citizen of the United States, residing at Philipsburg, in the county of Warren and State of New Jersey, have invented a new and useful 5 Rotary Engine, of which the following is a specification.

This invention, while relating more particularly to improvements in means for driving rotary drills and the like, is not limited to this employment, but is clearly applicable to use in many relations where rotary motion is desired and motive fluid may be secured.

The principal object is to provide a novel, 15 simple, and comparatively compact structure capable of developing power and high speed and composed of parts that are simple in their nature and are not liable to derangement. In this last connection one of the 20 objects is to provide a valve-operating mechanism that is comparatively simple in its make-up and is actuated by a single operating device to control the movements of the motor.

Another object is to provide a structure 25 wherein the working parts are completely inclosed, whereby the motor is peculiarly adapted for use under water.

In the drawings, Figure 1 is a vertical sectional view through the preferred embodiment of the invention, said invention, however, being not limited to such embodiment. Fig. 2 is a horizontal sectional view through the same. Fig. 3 is a sectional view taken at right angles to Fig. 2. Fig. 4 is a vertical sectional view substantially on the line 4-4 of Fig. 2. Fig. 5 is a detail sectional view through the valve mechanism. Fig. 6 is a sectional view on the line 6-6 of Fig. 2.

Similar reference-numerals designate corresponding parts in all the figures of the drawings.

In the embodiment illustrated an outer casing is employed, which comprises an annular wall 7 and heads 8, one of said heads being preferably integral with the annular wall, the other being detachably secured thereto. The annular wall 7 is substantially elliptical in cross-section, as will be apparent by reference to Fig. 1, wherein a true circle is shown in dotted lines. Arranged within the casing and completely inclosed thereby are the working parts of the motor.

Angularly-disposed cylinders 9 are provided, having outer trunnions 10, journaled eccentrically in the heads of the casing, said trunnions being mounted in take-up collars 11, threaded into said heads. Each cylinder preferably has an integral head at one end and a detachable head secured to its opposite end.

It will be observed by reference to Fig. 1 that the axis of rotation of the cylinders is located in the plane of the minor axis of the casing. The cylinders 9 are also provided on their inner sides with trunnions, one of said trunnions 12 being larger than the other and having a socket 13, in which said other, (designated 14,) is detachably fitted. Extending across the socket 13 is a holding device in the form of a pin 15, said pin being received in a seat 16, formed in the trunnion 14. Reciprocating pistons 17 are mounted in the cylinders and have piston-rods 18 projecting beyond the opposite ends thereof. These piston-rods are provided with terminal yokes 19, in which are journaled rollers 20, that operate against the inner face of the said substantially elliptical wall 7.

A valve in the form of a disk 21 is mounted upon the interlocked trunnions 12 and 14, said trunnions rotating in said valve-disk. This disk has curved chambers 22 opening through the opposite sides of the same and having their ends spaced from each other. Ports 23, formed in the walls of the cylinders 9 and contiguous to the ends thereof, communicate alternately with the chambers upon the rotation of the pistons. Said chambers are also provided with end ports 24, that open through the opposite peripheral portions of the valve, as shown in Fig. 5. The valve is surrounded by a sectional casing-ring 25, and threaded into the diametrically opposite portions of the ring are supply and exhaust conduits 26 and 27, said conduits extending through the peripheral wall 7 of the casing. It will be seen by reference to Fig. 5 that by this arrangement of the parts the valve-disk may be turned so that one of the chambers will be in communication with the supply-conduit 26, while the other will communicate with the exhaust 27, or said other may be placed in communication with the supply, in which case the first-mentioned will be connected with the exhaust. Further-

more, the valve may be turned so that both the supply and the exhaust are out of communication with the chambers. For the purpose of turning the valve an operating-sleeve 28 is journaled on the supply-pipe 26, said sleeve extending through the casing and having at its outer end a knurled or roughened portion 29. Its inner end has a series of teeth 30, that mesh with a rack 31, carried by the valve, as shown in Figs. 4 and 6. The sleeve 28 is maintained in place by the supply pipe or conduit 26, which conduit has at its outer end an annular flange 32, engaging against an internal annular shoulder 33 of the sleeve 28. It will thus be apparent that when the pipe 26 is screwed into the casing 25 the sleeve will be held against longitudinal displacement, while its rotation is permitted.

Motive fluid in the form of compressed air, steam, or the like is supplied from any suitable source to the pipe or conduit 26. It will be apparent that if the sleeve 28 is turned so that the ports 24 of the valve are out of alignment with the supply pipe or conduit 26 motive fluid will be cut off from both cylinders. If, however, the valve is turned so that one of the ports 24 is brought into communication with the supply-pipe, the other port will communicate with the exhaust. Motive fluid therefore will enter one of the chambers, and as the ports of the cylinders successively communicate with opposite sides of the said chamber said motive fluid will successively enter the cylinders and drive the pistons alternately in opposite directions. The ports 23 of the cylinders alternately communicate with both chambers of the valve, thereby alternately receiving supplies and exhausting. To reverse the engine, it is only necessary to turn the valve so that the chamber first in communication with the exhaust is brought into communication with the supply, whereupon the former chamber, through which the supply of motive-fluid is passed, will communicate with the exhaust.

From the above and from the drawings it will be apparent that the structure is very simple and exceedingly compact. The parts also are of a nature that are not liable to derangement and are capable of very high speed. The annular wall 7 constitutes a track or guide for the bearing-rollers and because of its peculiar shape and the disposition of the axis of rotation of the revolving part there is no lost motion and the highest degree of efficiency is secured. Furthermore, in this particular embodiment the movable parts are entirely inclosed in a tight casing, thus making the motor peculiarly applicable for use under water or in places where the movable parts might be deleteriously affected by outside influences. In practice oil can be placed directly within the casing, so that the parts will be efficiently lubricated. The valve structure, as will be apparent, is very

simple, a single valve being provided for both cylinders to control the starting, stopping, and reversing of the motor. Moreover, all these controlling operations are effected by the action of one device—namely, the sleeve 28. The wear between the rotating cylinders and the interposed valve can be readily taken up without dismembering the parts by merely screwing in the take-up collars 11, and thus steam-tight joints can be easily maintained.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus fully described my invention, what I claim as new, and desire to secure by Letters Patent, is—

1. In a rotary motor, the combination with an annular track or guide, of journal-bearings adjustable toward and from each other, separable angularly-disposed rotatable cylinders journaled in the bearings and located between them, said cylinders being held together by the bearings, and pistons operating in the cylinders and having bearing devices that operate against the track or guide.

2. In a rotary motor, the combination with a casing having an annular substantially elliptical wall and end walls, of journal-bearings threaded into the end walls and adjustable toward and from each other, separable angularly-disposed rotatable cylinders located within the casing and journaled in the bearings, said cylinders being held together by the bearings, and reciprocatory pistons operating in the cylinders and having bearing devices projecting from the opposite ends of the cylinders and operating against said elliptical wall.

3. In a rotary motor, the combination with angularly-disposed rotatable cylinders located side by side, of reciprocatory pistons operating therein, and valve mechanism interposed between the adjacent sides of the cylinders for controlling the supply of motive fluid to and the exhaust of motive fluid from the cylinders.

4. In a rotary motor, the combination with angularly-disposed rotatable cylinders located side by side, of reciprocatory pistons operating in the cylinders, and a single valve device interposed between the adjacent sides of the cylinders for controlling the supply of motive fluid to and the exhaust of motive fluid from both cylinders.

5. In a rotary motor, the combination with angularly-disposed rotatable cylinders located side by side, of a trunnion connection

between the cylinders, reciprocatory pistons operating in the cylinders and rotatable therewith, and valve mechanism interposed between the adjacent sides of the cylinders 5 and mounted on the trunnion connection.

6. In a rotary motor, the combination with angularly-disposed rotatable cylinders located side by side, of reciprocatory pistons operating in the cylinders, valve mechanism 10 interposed between the adjacent sides of the pistons for controlling the supply of motive fluid to and the exhaust of motive fluid from the cylinders, and journal-bearings for the cylinders located outside the same and movable toward and from each other to hold the cylinders against the valve mechanism. 15

7. In a rotary motor, the combination with a casing including an annular wall and end walls, of rotatable angularly-disposed cylinders located side by side within the casing, reciprocatory pistons operating in the cylinders and carrying devices that bear against the annular wall of the casing, a trunnion connection between the cylinders, a valve 20 device rotatably mounted on the trunnion and controlling the supply of motive fluid to and the exhaust of motive fluid from both cylinders, outstanding trunnions carried by the cylinders, and journal-bearings therefor 25 mounted in the end walls of the casing and movable toward each other to hold the cylinders against the valve device. 30

8. In a rotary motor, the combination with a casing having an annular wall, of angularly-disposed cylinders rotatably mounted within the wall, valve mechanism located between the cylinders, supply and exhaust pipes passing through the annular wall and connected to the valve mechanism, and pistons operating in the cylinders and having devices that 35 operate against the wall on opposite sides of the pipes.

9. In a rotary motor, the combination with a casing having an annular wall, of angularly-disposed cylinders located side by side within the casing, and rotatable therein, a valve device located between the cylinders and controlling the supply of motive fluid to and the exhaust of motive fluid from both cylinders, 40 oppositely-extending supply and exhaust pipes passing through the annular wall of the casing and communicating with the valve device, and pistons operating in the cylinders and having piston-rods projecting beyond 45 opposite ends of the same, said piston-rods having devices that bear against the inner face of the annular wall on opposite sides of the pipes. 50

10. In a rotary motor, the combination with a rotary cylinder, of a reciprocatory piston operating therein, said cylinder having supply and exhaust ports, a rotary valve having separate chambers provided with ports, said cylinder-ports moving into and 55 out of communication with said chambers,

motive-fluid and exhaust conduits coacting with different portions of the valve, said valve being movable with respect to the conduits to carry ports of each chamber thereof into communication with both conduits, 70 whereby said chambers may be made to receive either supply or exhaust motive fluid.

11. In a rotary motor, the combination with a rotary cylinder, of a reciprocatory piston operating therein, said cylinder having supply and exhaust ports, a rotary valve-disk located alongside the cylinder and having separate chambers provided with end ports, said cylinder-ports moving into and out of communication with the chambers, 75 80 motive fluid supply and exhaust conduits coacting with opposite peripheral portions of the valve, said valve being movable with respect to the conduits to carry different of its ports into communication with each conduit, 85 whereby said chambers may be made to constitute either supply or exhaust chambers.

12. In a rotary motor, the combination with angularly-disposed rotary cylinders having ports, of reciprocatory pistons operating in the cylinders, a valve located between the cylinders and having supply and exhaust chambers with which the cylinder-ports align, and supply and exhaust conduits 90 communicating with said chambers. 95

13. In a rotary motor, the combination with angularly-disposed rotary cylinders having ports, of reciprocatory pistons operating in the cylinders, a valve-disk located between the cylinders and having supply and exhaust chambers opening through opposite sides of the same, the ports of the cylinders aligning with the chambers during the rotation of said cylinders, and supply and exhaust conduits communicating with peripheral portions of said chambers. 100 105

14. In a rotary motor, the combination with angularly-disposed rotary cylinders having ports in their inner opposing sides, of reciprocatory pistons operating in the cylinders, a normally stationary adjustable valve-disk located between the cylinders and having supply and exhaust chambers opening through opposite sides of the same, the cylinder-ports aligning with the chambers during the rotation of the cylinders, said chambers also having peripheral ports, supply and exhaust conduits coacting with opposite portions of the valve-disk, the chamber-ports of said disk being movable into and out of co-action with the conduits, and means for adjusting the valve. 110 115 120

15. In a rotary motor, the combination with a rotary cylinder, and a reciprocatory piston mounted therein, of a movable valve 125 controlling the supply of motive fluid to the cylinder, said valve having a chamber, and a port communicating therewith, said cylinder moving into and out of communication with the chamber, a conduit with which the port 130

moves into and out of communication upon the movement of said valve, and means for moving the valve.

16. In a rotary motor, the combination 5 with a rotary cylinder, and a reciprocatory piston mounted therein, of a movable valve controlling the supply of motive fluid to the cylinder, said valve having a port, a conduit with which the port moves into and out of 10 communication upon the movement of said valve, and means surrounding the conduit and connected to the valve for moving the same.

17. In a rotary motor, the combination 15 with a rotary cylinder, and a reciprocatory piston mounted therein, of a rotary valve controlling the supply of motive fluid to the cylinder, said valve having a port and teeth, a conduit with which the valve-port moves 20 into and out of communication upon the movement of said valve, and a sleeve journaled on the conduit and having teeth meshing with the teeth of the valve.

18. In a rotary motor, the combination 25 with angularly-disposed cylinders, of reciprocatory pistons operating therein, interlocked trunnions carried by the inner sides of the cylinders, and means for supplying motive fluid to the cylinders.

30 19. In a rotary motor, the combination with angularly-disposed cylinders, of reciprocatory pistons operating therein, interlocked trunnions carried by the inner sides of the cylinders, and means for supplying 35 motive fluid to the cylinders, said means including a valve in which the interlocked trunnions are journaled.

20. In a rotary motor, the combination 40 with angularly-disposed cylinders, of reciprocatory pistons operating therein, a socketed trunnion carried by one cylinder, another trunnion carried by the other cylinder and fitting in the socket of the first-mentioned trunnion, and means for supplying 45 motive fluid to the cylinders.

21. In a rotary motor, the combination 50 with angularly-disposed cylinders, of inner and outer trunnions carried thereby, the inner trunnion of one cylinder having a socket and a holding device therein, the inner trunnion of the other cylinder fitting 55 in the socket and having a seat to receive the holding device, reciprocatory pistons operat-

ing in the cylinders, and means for supplying motive fluid to the cylinders.

22. In a rotary motor, the combination 55 with angularly-disposed cylinders, of reciprocatory pistons operating therein, outer trunnions carried by the cylinders, a valve located between the cylinders and controlling the supply of motive fluid to both, and a take-up device mounted on one of the outer trunnions and bearing against the cylinder to urge the same toward the other and take up the wear between said cylinders and the 60 valve.

23. In a rotary motor, the combination with a casing having heads, of take-up collars threaded into said heads, angularly-disposed cylinders having outer trunnions 70 journaled in collars, reciprocatory pistons operating in the cylinders, inner interlocked trunnions carried by the cylinders, a valve mounted on the interlocked trunnions and controlling the supply of motive fluid to both 75 of said cylinders, and means for conducting a supply of motive fluid to, and the exhaust from said valve.

24. In a rotary motor, the combination 80 with a casing comprising a substantially elliptical wall, and heads, of take-up collars threaded eccentrically into the heads, angularly-disposed cylinders having interlocked inner trunnions, and outer trunnions journaled in the take-up collars, said cylinders 85 having ports through their inner sides, a rotary valve-disk mounted on the interlocked inner trunnions and having chambers with which the cylinder-ports communicate, supply and exhaust conduits having their 90 inner ends disposed contiguous to opposite portions of the valve, said valve having ports that are movable into and out of communication with the conduits, reciprocatory pistons operating in the cylinders and having 95 piston-rods projecting beyond the opposite sides of the same, and rollers journaled on the ends of the piston-rods and operating against the said elliptical wall of the casing.

In testimony that I claim the foregoing as 100 my own I have hereto affixed my signature in the presence of two witnesses.

WILLIAM A. KELSO.
